UNITED STATES PATENT OFFICE.

ALBERT H. KENNEWEG, OF BROOKLYN, NEW YORK.

LATCH.

1,286,344.

Specification of Letters Patent.

Patented Dec. 3, 1918.

Application filed April 17, 1918. Serial No. 229,079.

To all whom it may concern:

Be it known that I, ALBERT H. KENNEWEG, a citizen of the United States, residing at Brooklyn, in the county of Kings and 5 State of New York, have invented certain new and useful Improvements in Latches, of which the following is a specification.

My invention relates to latches, having double throw bolts.

10 An important object of the invention is to provide a latch of the above mentioned character, having means for holding a bolt in the single throw position, such means being released to permit of the full throw movement of the bolt, by the inward movement of the bolt, upon the closing movement of the door.

20 A further object of the invention is to provide a latch of the above mentioned character formed of few and simple parts, and which is accordingly simple in construction, and inexpensive to manufacture.

25 Other objects and advantages of the invention will be apparent during the course of the following description.

In the accompanying drawings forming a part of this specification and in which like numerals are employed to designate like parts through the same,

30 Figure 1 is a longitudinal sectional view taken on line 1—1 of Fig. 4,

Fig. 2 is a similar view taken on line 2—2 of Fig. 4,

Fig. 3 is a side elevation of the latch,

35 Fig. 4 is a similar view with the side plate removed, showing the bolt in the outer double throw position,

Fig. 5 is a similar view showing the bolt in the innermost position, the same being 40 moved thereto by means of the cam,

Fig. 6 is a similar view showing the bolt in the outer single throw position,

Fig. 7 is a similar view showing the bolt in the innermost position, the same being 45 moved thereto by the closing movement of the door,

Fig. 8 is a side elevation of a lock-lever, and,

Fig. 9 is an edge elevation of the same.

50 In the drawings, wherein for the purpose of illustration is shown a preferred embodiment of my invention, the numeral 10 designates the casing of the latch, provided upon

one side with a main opening 11, covered by a plate 12. The plate 12 is held in place 55 by a screw 13, engaging a lug 14, while any other suitable means may be employed for this purpose.

The numeral 15 designates a slide or reciprocatory bolt operating through an opening 16 in one end of the casing 10, and having its outer end beveled in opposite directions, as shown at 17, whereby the latch may be used upon either side of a door. The bolt 15 is provided with an arm 18, rigidly secured 60 thereto, and arranged within the casing 10. The arm 18 is provided at its free end with a lateral extension 19, disposed at a right angle with relation thereto. The bolt 15 has a rod 20 rigidly secured thereto, which is 65 mounted to slide within an opening in the lug 14, as shown. The rod 20 has a head 21 rigidly secured thereto which limits the outward movement of the bolt 15. The bolt 15 is urged outwardly by a compressible coil 70 spring 22, surrounding the rod 20, and confined between the bolt 15 and the lug 14, as shown.

As more clearly shown in Fig. 2, the closed side of the casing 10 is provided with a 80 transverse opening 23, rotatably receiving a pin or spindle 24, having a knob 25 rigidly secured to the outer end thereof, to turn the same.

The numeral 27 designates a cam, which is 85 rigidly secured to the pin or shaft 24. This cam is provided with a shoulder 28 and a radial extension or finger 29. Surrounding the pin 24 is a torsional coil spring 30, one end of which is anchored thereto, as shown 90 at 31, while its opposite end is anchored to a stationary stop or lug 32, as shown. The stop 32 is disposed beneath and in the path of travel of the radial extension 29 and limits the forward turning movement of the 95 cam, which turning movement is effected by the spring 30.

The numeral 33 designates a lock-lever, the forward end of which is preferably beveled and adapted to engage a beveled shoulder 34 of the bolt 15. The lock-lever 33 is pivoted to the casing 10, as shown at 35, and a latch element 36 is also connected with the pivot element 35 to swing thereon. The lock-lever 33 is swung upwardly by means 100 of a leaf spring 37, anchored to the same, as

- shown at 38. This leaf spring is coiled about the pivot or screw 35, and its opposite end is anchored to the latch element 36, as shown at 39. The spring 37 functions 5 to swing the lock-lever 33 upwardly and the latch element 36 forwardly. The latch element 36 is provided at its upper end with a longitudinal extension 40, and with a forwardly projecting shoulder 41.
- 10 The numeral 45 designates disks, pivoted upon opposite sides of the plate 12. One disk 45 carries a lug 46. The disks 45 may be connected by a tubular element 47, adapted for the reception of a key, for turning the 15 disks. A disk 48 is rigidly secured to one end of the shaft 24, and carries a lug 49, to contact with the lug 46. It is obvious that by means of a proper key, the shaft 24 may be turned to move the bolt 15 inwardly. A 20 pin tumbler lock may also be employed for this purpose.

The operation of the latch is as follows:

- When the bolt 15 is in the outer double throw position, as indicated in Fig. 4, the 25 same may be drawn to the innermost position, as indicated in Fig. 5, by a turning movement of the knob 25. When the knob is turned, the cam 27 first swings the lock-lever 33 downwardly, as it is contacting therewith, whereby the bolt 15 is free to move inwardly when the radial extension 29 contacts with the extension 19 of the arm 18. As shown in Fig. 5, the cam 27 has been 30 turned to its rearmost position, with the bolt 15 in the innermost position, and the shoulder 28 beneath the shoulder 41. When the knob 25 is released, the spring 22 moves the bolt 15 to the outer single throw position, as indicated in Fig. 6, the bolt being 35 now held against further outward movement by the shoulder 28 engaging beneath the shoulder 41 of the latch element 36. It is obvious that the knob 25 may be turned to shift the bolt 15 from the outer single throw 40 position to the innermost position. When the door is closed, the bolt 15 is moved inwardly by contacting with the keeper, thus causing the rearward movement of the arm 18, whereby the extension 19 contacts with the extension 40 of the latch element 36. The latch element 36 is therefore swung 45 rearwardly so that the shoulders 28 and 41 are disengaged, whereby the spring 30 at once returns the cam 27 to its normal starting position. The bolt 15 will now move 50 forwardly or outwardly to the double throw position, as indicated in Fig. 4, at which time the lock-lever 33 will swing upwardly and be positioned behind the bolt, thereby locking the same against further inward 55 movement, until the lock-lever 33 is depressed by manipulation of the cam 27.

It is to be understood that the form of my invention herewith shown and described 60 is to be taken as a preferred example of

the same, and that various changes in the shape, size, and arrangement of parts may be resorted to without departing from the spirit of the invention or the scope of the 70 subjoined claims.

Having thus described my invention, what I claim is:—

1. A latch of the character described comprising, a casing, a reciprocatory bolt slidably engaging the casing, an arm attached to the bolt and provided with a lateral extension, a pivoted cam having a shoulder and a radial extension to engage with the first named extension, a pivoted lock-lever disposed to have one end thereof move into the path of travel of the bolt and arranged to contact with the cam and be shifted thereby, and a pivoted latch element having a shoulder to engage with the first named shoulder for locking the pivoted cam 80 against movement in one direction and an extension arranged in the path of travel of the lateral extension.

2. A latch of the character described comprising, a casing, a reciprocatory bolt slidably engaging the casing, an arm attached to the bolt and provided with a lateral extension, a pivoted cam having a shoulder and a radial extension to engage with the first named extension, a spring to move the 95 bolt outwardly, a spring to return the pivoted cam to its starting position, a pivoted lock-lever disposed to have one end thereof move into the path of travel of the bolt and arranged to contact with the cam and be shifted thereby out of the path of travel of the bolt, a pivoted latch element having a shoulder to engage with the first named shoulder and hold the cam against turning movement in one direction and an extension 100 arranged in the path of travel of the lateral extension, and yielding means to move the lock-lever and latch element to the active position.

3. A latch of the character described comprising, a casing, a reciprocatory bolt slidably engaging the casing, an arm secured to the bolt, a spring to move the bolt outwardly, a pivoted lock-lever arranged to have one end thereof move into the path of travel of the bolt, yielding means to move the pivoted lock-lever to the active position, a pivoted cam to move the lock-lever to the inactive position and having means to engage with the arm and move it rearwardly, yielding means to move the cam to the starting position, and releasable means for holding the cam against movement in one direction and adapted to be operated by said arm.

4. A latch of the character described comprising, a casing, a movable bolt associated with the casing, an arm secured to the bolt to move it in one direction, a spring to move the bolt outwardly, a movable lock lever 130

adapted when moved to the active position to hold the bolt against inward movement; means to move the lock lever to the active position, a cam arranged to contact with the lock lever and shift the same to the inactive position, yielding means to move the cam to the starting position, and releasable means for holding the cam against turning move-

ment in one direction and adapted to contact therewith and be operated by said arm. 10

In testimony whereof I affix my signature in presence of two witnesses.

ALBERT H. KENNEWEG.
